RAILWAY JOURNAL BOX

Arthur E. Le Gare, St. Louis, Mo., assignor to General Steel Castings Corporation, Granite City, Ill., a corporation of Delaware

Application July 8, 1932. Serial No. 621,355

3 Claims. (Cl. 105—79)

This invention relates to railway rolling stock and consists in a novel driving box and spring saddle structure particularly adapted for use in locomotives.

It is the usual practice in locomotive construction to mount a separately formed spring saddle member upon the upper wall of the driving box, the upper part of the saddle serving as a seat for a spring or equalizer member forming part of the spring equalizing system supporting the locomotive frame. With such an arrangement there is a tendency for the saddle to tilt inwardly, drawing the supported spring out of alignment and unevenly transferring the load to the bearing brass and journal. Tilting of the saddle also causes excessive wearing of the inner lower edge portion of the saddle and of the abutting portion of the driving box, and frequently the saddle inclines so as to bear against the adjacent portion of the locomotive underframe causing friction between and wear of these parts.

Also the usual construction necessitates the provision of suitable reinforcing flanges on the upper part of the driving box which increase the necessary vertical clearance between the journal and frame, and which, because of the necessary clearance between the spring hangers and boiler lagging, limit the depth of the adjacent part of the frame wheel piece.

One object of the present invention is to strengthen the driving box and stabilize the spring saddle by forming these parts in a novel integral structure.

Another object is to utilize the spring saddle as a reinforcement for the upper part of the driving box, permitting elimination of the usual box flanges and thereby reducing the length of the box.

These objects and others are attained by the structures illustrated in the accompanying drawing in which—

Figure 1 is a side view illustrating a locomotive driving box and a portion of the underframe and spring equalizer system.

Figure 2 is a half vertical transverse section taken on the line 2—2 of Figure 1.

Figure 3 is a top view of the driving box.

Figure 4 is a side view of the same.

The novel driving box structure is illustrated as applied to an integral locomotive underframe or bed structure including box section backbone member 1, wheel pieces 2 projecting sidewardly therefrom and including pedestals 3, and vertical transverse reinforcing webs 4 extending from

side to side of the underframe between the pedestals. The pedestals are reinforced by vertical longitudinal walls 24 extending along the side of the underframe and merging with the ends of webs 4. The frame is supported by a spring 60 equalizing system including elliptic springs 23, hangers 25, and equalizer bars 26 pivoted at 27 to the vertical walls 24.

The driving box includes the usual hollow body portion having an upper wall with an arcuate under-surface for seating bearing brass 5 and being open at the bottom to receive a cellar 6 for waste or other lubricating material. The box and cellar at the lower edges have lugs 7 and 8, respectively, receiving bolts 9 for supporting the cellar. The box is supported between the pedestals by a pedestal binder 10 bolted to the under-surface of the bed. The box has side flanges 11 receiving the pedestals 3 and plane intermediate side walls 12 bearing against suitable liners on the inner surfaces of the pedestals. A wedge 13 is inserted between one of the pedestals and the adjacent side of the box, the wedge being provided with an automatic adjusting device 14.

In the present embodiment of the invention, the inner and outer walls of the driving box include plane faces 15 and 15a, respectively, which are offset from the planes of the flanges 11, the outer crescent-shaped face 15 opposing the driver 85 hub 19. The flanges 11 are extended upwardly above the body portion of the box to form spaced saddle-forming walls 16 reinforced by diagonal ribs 17. The inner wall 16 extends through an opening 18 in the top web of the wheel piece 2. Mounted on the upper extremities of the walls 16 is a spring seat 20 having grooves in the lower surface for adjusting shims 21 and the upper extremities of the walls. The upper surface of the spring seat is substantially of U-section 95 for receiving the lower portion of band 22 of elliptic spring 23.

With the use of the present invention the construction and assembly of the driving box and spring saddle is materially simplified while at the same time these parts are strengthened and tilting of the spring saddle on the box is prevented. The integral spring saddle adequately reinforces the upper wall of the box, permitting the elimination of the usual reinforcing flanges. This decreases the necessary vertical clearance between the journal and underframe and provides adequate space between the boiler (not shown) and the frame for the spring hangers.

Moreover, disassembly of the boxes and wheels 110

from the underframe is no more difficult with the use of the integral spring saddle, and the frame need not be raised higher, than is the case where the saddle is separately formed. With the use of the present invention, raising of the underframe causes the upper web of the wheel piece 2 to engage the spring seat 20, lifting the same with the supported spring from the saddle walls 16 and permitting the wheel piece to clear the saddle and driving box.

The invention is not limited to use with integral locomotive underframes but may advantageously be applied to any vehicle in which a frame supporting member is carried directly by the journal box but must be spaced substantially above the same. Also, the features of the invention may be utilized with other spring equalizer arrangements, as for instance, where a rigid equalizer bar is supported on top of the box and elliptic springs are carried from the ends of the bars. These and other details of the embodiment illustrated may be modified without departing from the spirit of the invention, and the exclusive use of all such modifications as come

within the scope of the appended claims is contemplated.

What is claimed is:

1. A locomotive driving box member having integral spaced upwardly disposed walls constituting a spring saddle, and a separable spring seat member connecting the tops of said walls.

2. In combination, a locomotive driving box structure having a body part and spaced walls extending substantially above said part and constituting an integral spring saddle, and a spring seat element connecting said walls and having grooves in the lower surface receiving the upper extremities thereof.

3. In combination, a locomotive driving box structure having a body part and spaced walls extending substantially above said part and constituting an integral spring saddle, a spring seat element connecting said walls and having grooves in the lower surface receiving the upper extremities thereof, and spring adjusting shims inserted in said grooves.
